UNITED STATES PATENT OFFICE.

CHARLES JAMES, OF YOUNGSTOWN, OHIO.

LOCOMOTIVE DRIVING-BOX.

1,292,791.

Specification of Letters Patent.

Patented Jan. 28, 1919.

Application filed August 18, 1917. Serial No. 186,989.

To all whom it may concern:

- Be it known that I, CHARLES JAMES, a citizen of the United States, residing at Youngstown, in the county of Mahoning and State of Ohio, have invented a certain new and useful Improvement in Locomotive Driving-Boxes, of which the following is a full, clear, and exact description, reference being had to the accompanying drawings.
- 10 The general object of this invention is to provide a simple and effective locomotive driving box so constructed and arranged that the worn bearings may be replaced quickly and with little labor, and without requiring dropping of the wheels and the attendant disconnections. Another object is to insure the bearing members being firmly held in place while in use, though easily released for removal. Still another object is
- 15 to provide a simple and efficient thrust bearing carried on the driver side of the box for receiving the lateral thrust of the wheel.
- 20 My invention is clearly illustrated in the drawings, which show a preferred embodiment of it, and the essential and novel characteristics are summarized in the claims.
- 25 In the drawings, Figure 1 is an inner end view of the driving box with the cellar removed; Fig. 2 is a plan of the box; Fig. 3
- 30 is a vertical cross section in a plane parallel with the end of the box and looking away from the driving wheel; Fig. 4 is a vertical cross section through the axis of the driving axle; Fig. 5 is a perspective of the arcual wedge for locking the bearing brass in place; Fig. 6 is an end elevation of the box from the driving wheel end; Fig. 7 is an elevation of the thrust bearing ring, removed.
- 35 In the drawings 10, 10 indicate two side walls of the box and 11 the arch-shaped top thereof; 12 and 13 indicate vertical flanges providing space between them for legs of the locomotive frame. The box is flattened at the top, as indicated at 14, to provide
- 40 seats for the spring saddle. Below the axle space is provided for the usual cellar.

In Figs. 1, 3 and 6, I have indicated by the circle A the locomotive axle, which is journaled in the driving box. 20 indicates the bearing member or brass mounted within the box which engages this axle and supports the weight thereon. This brass is crescent-shaped in cross section, having a cylindrical interior concentric with the axle, and a slightly conical exterior. The brass may be made in one or more parts but is

preferably of three pieces of about equal arcual extent as shown in the drawings. The frame of the box is recessed above the axle and at the sides, providing space in excess of that required for the brass. The box also has horizontal shoulders 16 on which the lower edge of the brass rests.

The outer surface of the brass 20 stands a suitable distance within the curved wall of the recess of the box, and into this recess is adapted to be driven an arcual wedge 30. This wedge is shown as consisting of a portion of a cone, the inner surface of which is concentric with the brass, the outer surface of which is slightly tapered inwardly toward the driving wheel end. The wall of the box-recess is complementary to this outer surface of the wedge.

The wedge 30 has at its inner end a radial flange 31 provided with openings through which studs may extend into the box. Suitable nuts 41 and 42, screwing onto these studs force the wedge tightly into place and thus force the brass down onto the horizontal shoulders 16 and effectively hold it in place. A radial flange 23 extending outwardly at the outer end of the brass prevents its moving away from the driver, should it become loose.

I prefer to provide some clearance between the end of the wedge 30 and the flange 23 and between the flange 31 and the adjacent face of the box, so that the wedge may be effectively forced in by the nuts 41 until the brass is tightly clamped in place. I prefer to provide notches 34 in the inner face of the wedge flange 31 to allow the introduction of a suitable pry to force the wedge outwardly when the nuts are removed. Such outward forcing of the wedge releases the brass and enables its convenient removal.

In order to make the brass take the lateral thrust of the axle, I prefer to extend it downwardly beneath the horizontal diameter of the axle, as shown clearly in Fig. 3, for example. The wedge extends to approximately the same distance. Where the axle has a reduced intermediate portion, a one-piece brass of more than half a circumference may be installed by placing it over the intermediate part and shifting it endwise into place. If the axle is not thus reduced, the brass is preferably made in sections, as shown, and this enables it to be placed about the axle and slid into place in the box. It

is called "a brass" whether made in one or more pieces. After it is in place the wedge is slid endwise into place and secured by the nuts.

To effectively resist the thrust of the wheel against the end of the box, I provide a bearing ring 50 which has a beveled outer edge 51 extending behind an overhanging arcual shoulder 17 on the box. To allow the convenient insertion of this ring I prefer to make the overhanging flange 17 extend only for the upper portion of the circumference, and I make the ring 50 in parts, each of which is inserted from below with its concave edge upward and then given a partial rotation about the axis into place. When in place, the sections of the ring are secured together, as, for example, by electric welding.

Figs. 6 and 7 indicate this thrust bearing ring as made in two halves welded on the lines 52 and 53. With this arrangement a half ring may be inserted from below and rotated about the axis until it is above the axle, then the other half of the ring may be placed below the axle and the two rotated together until their abutting ends come into the space below the axle, where such ends may be conveniently welded together. Then the two-part ring may be given a half rotation to bring the other abutting line beneath the axle, where these ends are welded together. Then the ring constitutes one complete whole. The overhanging flange 17 prevents any displacement of the ring, except possible rotation about its own axis. The possibility of such travel may be prevented by a pin driven through the ring at any suitable point.

The side frames 10 of the box carry any suitable cellar, in the usual manner. Such cellar is indicated at 60 in Fig. 6 and consists of a box-like member open above and adapted to be put in place from below or from the inner end and held by the pins 61 extending through ears 63 on the collar and through ears 18 at the lower ends of the box sides 10.

It will be seen that my driving box is very simple in construction. To remove the brass it is only necessary to jack up the locomotive to take the weight off the axle and remove the nuts 40 and 41 and pry out the arcual wedge, when the brass may be readily slid out of place. The new brass may be reinstalled and locked in position with corresponding ease. The thrust bearing ring may be readily put in place, and, when in place, will be effective in receiving the thrust of the wheel, and, when worn, the ring may be readily cut apart and removed without removing the axle or wheel.

Having thus described my invention, what I claim is:

1. In a locomotive driving box, the combi-

nation, with a box frame, of an arcual bearing adapted to be housed in the upper portion of the frame, an arcual wedge adapted to be forced into place between the bearing and frame, and means for holding such wedge in position.

2. In a locomotive driving box, the combination, of a frame through which the axle may extend, said frame having an arcual recess above the axle, a bearing in the form of a partial sleeve made in one or more parts and adapted to occupy such recess, shoulders carried by the box against which the lower edge of the bearing abuts, and a wedge in the form of a partial sleeve adapted to be forced into the space between the top of the bearing and box, said wedge having a flange at its end, and means for securing the flange to the box.

3. In a locomotive driving box, the combination of a frame through which the axle may extend, said frame having a recess above the axle, a bearing in the form of a partial sleeve adapted to occupy such recess, a wedge in the form of a partial sleeve adapted to be forced into the space between the top of the bearing and box, said wedge having a flange at its end, and means for securing the flange to the box.

4. In a locomotive driving box, the combination of a frame having side members and a top providing a downwardly facing curved internal seat, a bearing in the form of a partial sleeve adapted to embrace the upper portion of the axle and stand within the box beneath said seat, there being a space within the box outside of the sleeve, and an arc-shaped wedge member adapted to occupy such space and having at its larger end an outward flange, and bolts adapted to secure said flange to the box frame.

5. In a locomotive driving box, the combination of a frame having side members provided with horizontal shoulders and a top providing a downwardly facing curved internal seat, a bearing member in the form of a partial sleeve adapted to embrace the upper portion of the axle and rest at its lower edges on said horizontal shoulders, there being a space within the box outside of the sleeve, an arc-shaped wedge member adapted to occupy such space and having at its larger end an outward flange, and bolts adapted to secure said flange to the box frame.

6. In a locomotive driving box, the combination of a frame, a sectioned bearing member in the form of a partial sleeve adapted to embrace the upper portion of the axle and extend below the horizontal diameter and stand within a recess in the box, there being a space within the box outside of the sleeve, and an arc-shaped wedge member adapted to occupy such space while the lower edges of the bearing member rest on horizontal shoulders on the box.

7. In a locomotive driving box, the combi-

nation of a frame having side members and an internal recess, a bearing member in the form of a partial sleeve made in one or more pieces and adapted to embrace the upper portion of the axle and stand within said recess in the box, there being a space within the box outside of the sleeve, and a wedge member adapted to occupy such space, said bearing member having a radial outward flange at its inner end overhanging the wedge and preventing the outward movement of the bearing member from the box.

8. In a locomotive driving box, the combination of a frame having side members and a top providing a downwardly facing internal seat, a bearing member in the form of a partial sleeve made in one or more pieces and adapted to embrace the upper portion of the axle and stand within the box, there being a space within the box outside of the sleeve and beneath the seat, an arc-shaped wedge member adapted to occupy such space and having at its larger end an outward flange, and bolts adapted to secure said flange to the box frame, said bearing mem-

ber having an arcual flange at its inner end adapted to engage the wedge and prevent outward movement of the bearing member.

9. In a locomotive driving box, the combination of a frame, an arc-shaped bearing within the frame having a radial flange at the outer end, a wedge-member outside of said bearing and within the frame, and a thrust bearing at the outer end of the frame and lying around said radial flange. 30

10. In a locomotive driving box, the combination of a frame, an arc-shaped bearing within the frame having a radial flange at the outer end, an arc-shaped wedge-member outside of the bearing and within the frame 40 and overhung by said flange, means for securing the wedge member to the inner end of the box, and a thrust bearing on the end of the box, concentric with and substantially engaging the arcual edge of said flange and 45 held to the end of the box.

In testimony whereof I hereunto affix my signature.

CHARLES JAMES.
